US00D686497S

(12) United States Design Patent
Lewis et al.

(10) Patent No.: US D686,497 S
(45) Date of Patent:  Jul. 23, 2013

(54) CONTAINER LID

(75) Inventors: Audrey Henrietta Mary Lewis, Bath (GB); Christopher Ellis, Bristol (GB)

(73) Assignee: Mars, Incorporated, McLean, VA (US)

() Term: 14 Years

(21) Appl. No.: 29/414,242

(22) Filed: Feb. 27, 2012

(30) Foreign Application Priority Data

Aug. 26, 2011 (EM) 1291066-0001-0003

(51) LOC (9) Cl. 09-07

(52) U.S. Cl.

USPC D9/451; D9/438

(58) Field of Classification Search

USPC D9/600, 643, 667, 424-432, 434-435, D9/438, 451; D7/511, 514-515, 518, 521, D7/392.1; 206/457, 527, 540; 220/890

See application file for complete search history.

(57) CLAIM

The ornamental design for a container lid, as shown and described.

DESCRIPTION

The sole FIGURE is a top plan view of a container lid showing our design. Since the container lid is substantially flat, the side views are not shown.
